D3-220

AU

EX

D1938

OR

D 023,818

DESIGN.

C. H. LINDBERG.
SWORD SCABBARD.

No. 23,818.

Patented Nov. 27, 1894.

Witnesses:

H. B. Bradshaw
A. L. Phelps

Inventor
Charles H. Lindberg
By
Staley and Shepherd
Attorneys

UNITED STATES PATENT OFFICE.

CHARLES H. LINDBERG, OF COLUMBUS, OHIO.

DESIGN FOR A SWORD-SCABBARD.

SPECIFICATION forming part of Design No. 23,818, dated November 27, 1894.

Application filed October 5, 1894. Serial No. 525,042. Term of patent 7 years.

To all whom it may concern:

Be it known that I, CHARLES H. LINDBERG, a citizen of the United States, residing at Columbus, in the county of Franklin and State of Ohio, have invented and produced a certain new and original Design for Sword-Scabbards, of which the following is a specification, reference being had to the accompanying drawing hereto annexed and forming part thereof.

The figure of the drawing represents the outer or lower end portion of a sword scabbard upon which my design is employed.

The essential features of this design consist in a tip ornamentation or extension of the sword scabbard which is substantially of an oval form and which has formed in relief on its opposite edges two partial female figures, the latter terminating in leaf scrolls which run to the point of said tip plate, and a hand grasping a passion cross from which radiate light rays and above which is a flame, all of said parts being in relief.

a represents the substantially oval tip plate; b, the figures on opposite sides thereof, said figures being inclined inward and having on their inner shoulders inwardly and upwardly extended wings. These wings embrace the upper portion of a central oval space inclosed by a raised marginal portion c, said marginal portion embracing a group of radially arranged light lines, as shown. d represents the scrolls which are raised from the face of the plate a and form the side boundaries thereof. From the upper portion of the central oval space which is bounded by the raised frame c rises a hand e, within which is grasped the passion cross f, the latter being inclosed in a substantially circular space and being represented with light rays extending therefrom. 35 Above the passion cross is represented a flame g, the latter being raised from a stippled background and being arranged beneath a bowed rib h from which rises a standard i, the latter supporting on its upper end a burning 40 torch k. The body of the standard i is provided with raised laced or latticed work indicated at j, while on opposite sides of the standard are arranged leaf scrolls m of suitable pattern. All of the parts herein described 45 are raised from the face of the scabbard as indicated by the shade lines in the drawing. 50

What I claim is—

The design for a sword scabbard herein shown and described.

CHARLES H. LINDBERG.

In presence of—

C. M. VOORHEES,
C. C. SHEPHERD.